Inventor

ALBERT LEWINSON,
By his Attorney
Geo. F. Math

UNITED STATES PATENT OFFICE.

ALBERT LEWINSON, OF NEW YORK, N. Y.

SELF-LOCKING CONTAINER.

1,314,878.

Specification of Letters Patent. Patented Sept. 2, 1919.

Application filed April 24, 1919. Serial No. 292,389.

To all whom it may concern:

Be it known that I, ALBERT LEWINSON, a citizen of the United States, and a resident of the borough of Manhattan, city, county, 5 and State of New York, have invented certain new and useful Improvements in Self-Locking Containers, of which the following is a specification.

My invention is designed to afford simple, inexpensive but effective means whereby packages of various kinds may be safely delivered at residences and elsewhere without disturbing, or during the absence of, residents or occupants. While applicable 10 for the safe-guarding of delivered goods and merchandise generally, my device is especially adapted for the reception and retention of milk, groceries, and even mail matter, at houses, apartments, stores, etc.,— 15 20 in fact anywhere where it is necessary or desirable to leave packages to be subsequently acquired by the owners or purchasers.

The invention consists essentially in utilizing the weight of a package deposited in 25 the container or receiver to automatically shut and lock the door to the inlet or deposit aperture, as hereinafter more fully set forth and claimed specifically. An incidental feature also involves the closure of 30 the back or delivery aperture of the container by means of a door, or window, adjacent to the container.

In the accompanying drawings,

Figure 1, is a front view of my self locking container applied to and supported upon the frame of a door;

Fig. 2, is a vertical section thereof taken upon plane of line $x-x$, Fig. 1; showing the parts in normal position;

Fig. 3, is a like section showing the inlet door opened for the insertion of a package;

Fig. 4, is a like section showing the inlet door closed and locked by the weight of a package;

Fig. 5, is a horizontal section of the container taken upon plane of line $y-y$, Fig. 2.

The container C, is a box-like receptacle which is secured to and supported upon the frame F, of a door or window, in such position and relation to the same that when the door or window is shut it will close the rear or delivery aperture c, of said compartment C. In the accompanying drawings the container is shown as screwed to the frame F, of a door D, although any rear closure may be substituted therefor as may

be found most expedient in adapting the device to the varying conditions and requirements of use.

The front inlet or deposit aperture c', of the compartment C, is closed normally by a door b, hinged to a sill c², spring hinges h, h, being preferably used for the purpose which tend constantly to maintain the door in such normal position, while allowing it 65 to be opened my means of the handle b', unless locked as hereafter described.

The inlet door b, is formed with a rear extension b², below the sill c², and line of the hinges h, h, said extension b² being inside of and reaching nearly to the bottom of the compartment C, and having pivotally connected to it a shelf or false bottom b³, as indicated at b⁴, or any other suitable articulatory connection between the 75 false bottom b³, and the inlet door extension b², may be resorted to with like result.

When the inlet door b, is closed this shelf or false bottom b³, rests against a spring s, attached to the bottom c³, of the container 80 C, and in the absence of any excess of pressure exerted by the false bottom b³, against the resistance of the spring s, the latter sustains the said false bottom b³, in such position that its rear edge b^x, is clear of, and 85 out of contact with, the lower rear wall c⁴, of the container C, as shown in Fig. 2, so that the inlet door b, may be opened, as in Fig. 3, for the insertion of a package. When the door b, is thus opened the false bottom 90 b³, rests against a stop b⁶, attached to the extension b²,—said stop b⁶, being so positioned that when the inlet door b, is closed as in Figs. 2 and 4, it is clear of the false bottom b³, leaving the latter free to adapt 95 itself to the action of the spring s.

The presence of a weight W, on the false bottom b³, sufficient to overcome the resistance of the spring s, forces the rear edge b^x, of the said false bottom b³, into contact with 100 the lower rear wall c⁴, of the compartment C, as shown in Fig. 4, so that the inlet door b, cannot then be opened, because a pull upon the handle b', will only press said rear edge b^x, of the false bottom with still 105 greater force against the rear wall c⁴, of the compartment C. Hence the inlet door b, cannot be re-opened until the weight W, is removed through the rear or delivery aperture c, of the container; and if said 110 delivery aperture c, is closed by a door D, or equivalent means it is obvious that the

weight W ; (Fig. 4) which represents symbolically any package to be delivered, cannot be removed until such door or other closure is withdrawn from the rear of the container C . When however the weight W , is lifted from the false bottom b^3 , the spring s , immediately reasserts itself and returns the false bottom b^3 , to the normal position shown in Fig. 2, thereby allowing the inlet door b , to be again swung open when desired, as hereinbefore set forth.

I have herein shown the use of a flat spring s , on the bottom of the container C , for supporting the false bottom b^3 , in normal position with its rear edge b^4 , out of contact with the rear wall of the container, although any other form of spring may be substituted that will perform a like function, so that I do not limit myself in this respect, the essential feature being means that will effect the release of the false bottom when the weight W , is removed. It may be noted in this connection that the false bottom b^3 , articulately connected to the extension b^2 , of the inlet door b , acts substantially as a pawl provided with an automatic spring release, and that the door b , and its extension b^2 , act as a lever of the first order in relation to the false bottom. Furthermore the locking as well as the release is effected automatically,—the locking by the simple insertion of the package W , and the release by the removal thereof.

The device is inexpensive, simple both in construction and operation, and the operative parts few and fully inclosed and protected by the container.

What I claim as my invention and desire to secure by Letters Patent is,

1. A self-locking container of the character designated, comprising a compartment having an inlet aperture and a delivery aperture, a hinged closure for the inlet aperture formed with an offset extension beyond its hinge, within the compartment, a false bottom articulately connected with said extension and adapted when weighted to contact

with the inner wall of said container to prevent opening of said closure, said false bottom being of a length substantially equal to the distance between said hinge and the inner face of said wall, and resilient means mounted on the floor of the compartment and acting on the under face of said false bottom for effecting release of the false bottom when the weight is removed therefrom.

2. A self-locking container of the character designated, comprising a compartment having an inlet aperture and a delivery aperture, a hinged closure for the inlet aperture formed with an extension beyond its hinge, within the compartment, a false bottom articulately connected with said extension and adapted when weighted to contact with the inner wall of said container to prevent opening of said closure, said false bottom being of a length substantially equal to the distance between said hinge and the inner face of said wall, and a stop on said extension against which the false bottom rests when the closure is open.

3. A self-locking container of the character designated, comprising a compartment having an inlet aperture and a delivery aperture, a hinged closure for the inlet aperture formed with an extension beyond its hinge, within the compartment, a false bottom articulately connected with said extension and adapted when weighted to contact with the inner wall of said container to prevent opening of said closure, said false bottom being of a length substantially equal to the distance between said hinge and the inner face of said wall, and a stop on said extension against which the false bottom rests when the closure is open, said stop being positioned to be free from contact with said false bottom when the said closure is in its closed position.

ALBERT LEWINSON.
